UNITED STATES PATENT OFFICE.

EMIL VERSE, OF CHEMNITZ, GERMANY, ASSIGNOR TO MASCHINENFABRIK KAPPEL AKTIENGESELLSCHAFT, OF KAPPEL, CHEMNITZ, GERMANY, A COMPANY OF GERMANY.

SHUTTLE EMBROIDERY MACHINE.

1,427,564.

Specification of Letters Patent. Patented Aug. 29, 1922.

Application filed August 25, 1921. Serial No. 495,209.

(GRANTED UNDER THE PROVISIONS OF THE ACT OF MARCH 3, 1921, 41 STAT. L., 1313.)

To all whom it may concern:

Be it known that I, EMIL VERSE, a citizen of Germany, and a resident of Chemnitz, Germany, have invented certain new and useful Improvements in Shuttle Embroidery Machines (for which I have obtained patents in Germany numbered 344,345 and 347,261), of which the following is a specification.

10 This invention relates to shuttle embroidery machines wherein curved shuttles are reciprocated in curved shuttle races inclined at an angle of less than 90 degrees to the longitudinal axis of the machine.

15 In machines of this type it is necessary not only to propel the shuttle in a curved path within the curved shuttle race, but also to traverse the shuttle substantially at right angles thereto, owing to the inclination of 20 the shuttle race.

According to the present invention the shuttle is propelled in the usual manner by means of a driving element projecting from an oscillatory shaft, but instead of traversing the shuttle by axial displacement of the shaft as heretofore proposed the shuttle is traversed by means of axial displacement of a longitudinal member interposed between the driving element and the shuttles. In 30 this manner the weight of the parts which require to be longitudinally displaced is considerably diminished.

A further object of this invention is to minimize vibration of the machine frame, 35 due to reversal of movement during axial displacement of the longitudinal member first in one longitudinal direction and then in the other.

Reference will be hereinafter made to the 40 accompanying explanatory drawings whereon:

Fig. 1 is a fragmentary cross section showing the main parts of the shuttle mechanism.

Fig. 2 is a plan of Fig. 1.

45 Fig. 3 is a rear elevation of the mechanism.

Fig. 4 is a side view, partly in section, and Fig. 5 a plan showing a modified arrangement.

50 Figs. 6 and 7 are views corresponding to Figs. 4 and 5 showing a further variation.

Fig. 8 is a view corresponding to Fig. 1 showing a further development thereof and

Fig. 9 is a fragmentary rear view thereof.

As shown in Figs. 1, 2 and 3, the oscillatory driving shaft 1 carries arms or driving elements 2 supporting a longitudinal bar 3, the shuttles 4 being reciprocated within curved shuttle races 5 by means of drive pins 6. The shuttle races 5 are also inclined 60 at an angle of less than 90 degrees to the longitudinal axis of the machine (as clearly seen in Fig. 3).

The shaft 1 is mounted in bearings 7 which also support the shuttle race bar 9. The arms 2 are pivotally connected to the shaft 1 by means of sleeves 13 and hinge pins 14 and are also pivotally connected to the bar 3 by shackles 15. A shaft 11, toothed sector 12, rack 10 and guides 8 serve to draw 70 out the rear carriage in the usual manner when inserting the material. The hinge pins 14 and shackles 15 of the arms 2 enable the bar 3 to follow the inclination of the shuttle races during the oscillations imparted to it 75 from the oscillatory shaft 1, without necessitating axial displacement of the latter.

The displacement of the bar 3 may be effected in various ways. In Fig. 3 the bar 3 carries a roller 16 working in inclined 80 guides 17 fixed upon the shuttle race bar 9. In Figs. 4 and 5 the bar 3 is supported by brackets 18 slidable upon pins 19 projecting from levers 20 fixed upon the shaft 1. In Figs. 6 and 7 the arm 21 fixed upon the 85 shaft 1 is shaped at its extremity to form a guide for the sliding bar 3.

In order to minimize vibration of the machine frame due to the reversal of movement of the bar 3, the latter may be displaced longitudinally by the same driving mechanism as that effecting the oscillation of the shaft 1. As the longitudinal movement of the bar is small in comparison to its oscillatory movement, the mechanism may be designed 90 to provide very smooth operation of the machine. Such an arrangement is illustrated in Figs. 8 and 9. The shaft 1 is oscillated from a cam 22 by means of a lever 23, rods 24 and 25 and crank 26. The bar 3 is connected to the rod 25 by a link 27 and bell crank lever 28, the latter carrying a block 29 working in a notch or slot in the rod 25.

When the shaft 1 is oscillated, the rod 25 simultaneously effects longitudinal displacement of the bar 3 in accordance with the 105

inclination of the shuttle races 5, through the medium of the crank 28 and link 27.

Claims:

1. In a shuttle embroidery machine, a curved shuttle race inclined to the longitudinal axis of the machine, a shuttle within said race, an oscillatory driving shaft fixed against axial displacement, a longitudinal member carried by said shaft, and adapted to drive the shuttle and means for longitudinally displacing said longitudinal member in relation to the driving shaft.
2. In a machine as specified in claim 1, arms pivotally connected to the longitudinal member and to the shaft to permit of the longitudinal movement of said member relative to said shaft.
3. In a machine as specified in claim 1,

mechanism for effecting the oscillation of the shaft and for simultaneously displacing 20 the longitudinal member.

4. In a shuttle embroidery machine, a curved shuttle race inclined at an angle of less than ninety degrees to the longitudinal axis of the machine, a shuttle within said race, an oscillatory driving shaft fixed against axial displacement, a longitudinal member carried by said shaft and adapted to drive the shuttle, a reciprocating rod, means for reciprocating said rod, a crank connecting said rod and the shaft and a bell-crank connection between said rod and the longitudinal member for displacing the latter.

In testimony whereof I hereunto affix my signature.

EMIL VERSE.
